UNITED STATES PATENT OFFICE

2,591,823

SHOE MACHINE

Walter J. Janas, Lewiston, Maine, assignor to
United Shoe Machinery Corporation, Flemington, N. J., a corporation of New Jersey

Application August 6, 1948, Serial No. 42,819

10 Claims. (Cl. 12—17)

1

This invention relates to machines for use in the manufacture of shoes and particularly to a novel and improved machine for conforming the marginal portion of a sole facing to the edge of a sole member.

In certain well-known types of shoes such, for example, as slippers, the outsole comprises a sole member having a body portion of felt, or other relatively soft and compressible material, which is faced on one side with a piece of upper leather. This facing piece is larger than the sole member so as to provide a marginal portion that extends beyond the edge of the sole member, when these two parts are initially assembled, and, in the next step in the manufacture of a faced sole member of the aforementioned type, this marginal portion of the facing piece is folded around the edge of the sole member and secured in place, as by adhesive, to the opposite side of the sole member.

The aforementioned step is commonly performed by hand although machines for carrying out this folding operation have been proposed. These prior machines, however, merely turn the marginal portion of the facing piece upwardly into a position substantially parallel to the edge of the sole member and then fold it in over the opposite side thereof, without exerting any definite tension thereon so as to draw the marginal portion of the facing tightly around the edge of the sole member. Accordingly, with the facing piece thus rather loosely conformed to the edge of the sole member, when the sole member is applied to a shoe, the weight of the wearer may so compress the material of the body of the sole member as to produce unsightly bulges, or wrinkles, in the facing on the edge of the sole member.

It is an object of this invention to provide a novel and improved machine for conforming the marginal portion of a sole facing to the edge of a sole member in which the facing is tensioned so as to draw it tightly around the edge of the sole member. With this object in view, the herein illustrated machine is provided with tensioning means for seizing the marginal portion of a sole facing and drawing it snugly around the edge of a sole member, together with means for pressing the tensioned marginal portion against the opposite face of the sole member; the tensioning means and pressing means being arranged to operate progressively around the peripheral edge of the sole member. For supporting the sole member and its attached facing piece during the aforementioned tensioning and pressing operations, and in accordance with a feature of this invention, the herein illustrated machine is provided with a table which, preferably, is yieldably mounted so as to accommodate sole members of different thicknesses as well as sole members of non-uniform thickness. This table is pro-

2

vided with an upstanding deflecting member for turning the marginal portion of the facing piece upwardly into a position to be engaged by the tensioning and pressing means.

The above and other objects and features of the invention will appear in the following detailed description of the embodiment illustrated in the accompanying drawings, and will be pointed out in the claims.

While various types of tensioning and pressing instrumentalities which are available, for example, in prior cement lasting machines, may be utilized for drawing the marginal portion of the sole facing around the edge of the sole member and for pressing the tensioned marginal portion against the opposite side of the sole member, I have found that the tensioning and pressing instrumentalities of the lasting machine disclosed in United States Patent No. 2,411,827, granted on November 26, 1946, in the name of Joseph Fossa, are particularly well adapted for this purpose. Accordingly, the invention is here shown, for purposes of illustration only, as embodied in a lasting machine of that type.

In the drawings,

Fig. 1 is a view in side elevation of a machine embodying the features of this invention;

Fig. 2 is a view in front elevation of a portion of the machine shown in Fig. 1;

Fig. 3 is a plan view showing certain of the operating elements of the machine shown in Fig. 1, and

Fig. 4 is a view of the machine shown in Fig. 1 with parts in different operating positions.

Referring now to these drawings, the machine therein illustrated comprises the same operating instrumentalities as those of the lasting machine of the aforementioned patent, namely, a reciprocating gripper having a rear jaw 10 and a front jaw 12, a shoe bottom rest and lasting shield member 14, a presser feed foot 16, a feed-retaining finger 18 and an edge guide roll 20. These instrumentalities are all mounted on, and operated by mechanism contained within, a hollow head construction 22 having a lower portion 24 and a removable top portion 26. Also, the machine is provided with mechanism, operated by a treadle, not shown, for moving the shoe-bottom rest and lasting shield member, hereinafter referred to as the rest member, toward and away from the operating position in which it is shown, which mechanism is further adapted to hold the front jaw 12 away from the rear jaw 10 to facilitate the presentation of the work to the machine. Inasmuch as the construction and operation of these instrumentalities, as well as the operating mechanism therefor, is set forth in detail in the aforementioned patent, it will not be repeated here, and reference may be made to that patent for a description thereof.

For supporting a sole member S and its facing F, the illustrated machine is provided with a flat table 100 which is mounted so as to hold the sole member yieldingly up against the rest member 14, in the following manner. Fixed to the table 100, and extending downwardly therefrom, are four rods 102 which pass through bores 104 in bosses 106, formed integrally with a pair of angularly shaped brackets 110 and 112. These brackets are secured to the lower portion 24 of the head 22 by means of screws 114, 114 and are connected together by means of a transverse web 108. Surrounding each rod 102 is a coil spring 116 and these springs urge the table 100 upwardly, toward the rest member 14, to the extent permitted by stop nuts 118 carried by the rods 102.

When initially secured to the sole member S, the marginal portion of the facing F extends outwardly from the edge of the sole member in the manner shown in Figs. 2 and 3. For turning this marginal portion upwardly and into a position where it will be engaged by the gripper jaws 10 and 12, a deflecting member 120, having a curved upper end 122, is provided. Referring to Figs. 1 and 2, this deflecting member is secured for vertical adjustment on a bracket 124 by means of a screw 126 and a dowel pin 128, the member 120 being slotted at 130 for this purpose. The bracket 124 is fastened to a bar 132, by means of a screw 134, and this bar is adjustably secured to the web 108 by means of screws 136 which pass through an elongated slot 137 therein. The table 100 is recessed at 138 and 140, see Fig. 3, so as to provide clearance spaces for the deflecting member 120 and edge guide roll 20, respectively.

The operation of the machine which has just been described is as follows. The operator takes a sole member S and, after manually folding the outstanding margin of its facing F upwardly against the edge of the sole member, in a selecting location, places the sole member on the table 100 and slides it in under the rest member 14 so that the folded up portion of the margin of the facing is beneath the curved upper end 122 of the deflector 120 and the sole against the edge guide roll 20. Next, the operator depresses the treadle to swing the rest member 14 to its operative position as shown, in which the rest member contacts the upper surface of the sole member and extends beneath the margin of its facing, see Figs. 2 and 4. This movement of the rest member to its operative position releases the front jaw 12 and permits it to move toward the rear jaw 10, as in the machine of the above-mentioned patent, so that the gripper is now rendered operative to seize the margin of the facing and draw it snugly around the edge of the sole member, where it is immediately pressed against the upper surface of the sole member by the presser-feed-foot 16. It will be understood that the upper surface of the sole member, and/or the margin of the facing, have been previously coated with a suitable adhesive so that the margin of the facing is adhesively secured to the sole member.

The presser-feed-foot, while in pressing engagement with the margin of the facing, also moves in a direction to feed the sole member, while the feed-retaining finger 18 operates to apply additional pressure to the margin of the facing and also to hold the sole member against retrograde movement, during those intervals when the presser-feed-foot is back feeding and

the gripper is tensioning the margin of the facing. These tensioning, feeding and pressing instrumentalities operate in the same manner as in the machine described in the aforementioned patent.

As the sole facing F is thus being tensioned and pressed against the upper surface of the sole member S, progressively along the peripheral edge of the sole member, the operator merely guides and turns the sole member so as to keep its edge against the edge-guide roll 20, the deflecting member 120 with its curved upper end 122 initially turning the facing from its flat outstanding position upwardly to guide it into a location in which it will be engaged by the gripper jaws 10 and 12. Just before the operation has proceeded entirely around the periphery of a sole member, and as that portion of the margin of the facing which was first tensioned and pressed against the sole member is nearly reached, the operator depresses the treadle, thus withdrawing the rest member and rendering the gripper jaws 10 and 12 inoperative, and permits the presser-feed-foot 16 and feed-retaining finger 18 to continue to operate and complete the pressing of the margin against the sole member, this short remaining portion having been substantially tensioned by the effect of the gripper previously operating on opposite sides thereof.

During the above-described tensioning and feeding operations, the sole member S is yieldingly held up against the rest member 14 by the four springs 116, the stop nuts 118 being so adjusted as to permit this action with the particular thickness of sole member being handled. These springs, which are relatively light so as to merely support the weight of the table with a sole thereon, also yield to permit the table to move downwardly when a thicker portion of the sole member, e. g., the heel part which is built up by means of a wedge block W, is passing beneath the rest member 14, or when a sole member of greater thickness is presented to the machine.

While the invention has been herein illustrated as embodied in a machine of the type disclosed in the above mentioned patent, it will be understood, of course, that in its broader aspects it is not limited to the use of tensioning and pressing instrumentalities of the exact mechanical construction shown in said patent. Instead it is contemplated that the objects of this invention may be attained by associating the yieldable supporting table with other types of tensioning means.

Having described the invention, what I claim as new and desire to secure by Letters Patent of the United States is:

1. A machine for conforming the marginal portion of a sole facing piece to the edge of a sole member comprising, in combination, means for tensioning said marginal portion of the facing around the edge of the sole member, successively, in different locations along the edge of the sole member, means for pressing the marginal portion of the tensioned facing against the sole member in each location, and a yieldably mounted table for supporting the sole member and its facing piece during the operation of said tensioning and pressing means.

2. A machine for conforming the marginal portion of a sole facing piece to the edge of a sole member comprising, in combination, means for tensioning said marginal portion of the facing around the edge of the sole member, successive-

ly, in different locations along the edge of the sole member, means for pressing the marginal portion of the tensioned facing against the sole member in each location, and a yieldably mounted table for supporting the sole member and its facing, during the operation of said tensioning and pressing means, and means, associated with said table, for guiding said marginal portion of the facing to the tensioning means.

3. A machine for conforming the marginal portion of a sole facing piece to the edge of a sole member comprising in combination, a rest member, fixed during the operation of the machine, for engaging the sole member, means for tensioning said marginal portion of the facing around the edge of the sole member adjacent to said rest member, successively, in different locations along the edge of the sole member, means for pressing the marginal portion of the tensioned facing against the sole member in each location, and a table for holding the sole member up against the rest member during the operation of said tensioning and pressing means.

4. A machine for conforming the marginal portion of a sole facing piece to the edge of a sole member comprising, in combination, a rest member, fixed during the operation of the machine, for engaging the sole member, means for tensioning said marginal portion of the facing around the edge of the sole member adjacent to said rest member, successively, in different locations along the edge of the sole member, means for pressing the marginal portion of the tensioned facing against the sole member in each location, a table for holding the sole member up against the rest member, during the operation of said tensioning and pressing means, and means, associated with said table, for guiding said marginal portion of the facing to the tensioning means.

5. A machine for conforming the marginal portion of a sole facing piece to the edge of a sole member comprising, in combination, a rest member for engaging the sole member, means for tensioning said marginal portion of the facing around the edge of the sole member adjacent to said rest member successively in different locations along the edge of the sole member, means for pressing the marginal portion of the tensioned facing against the sole member in each location, a table for yieldably holding the sole member up against the rest member, during the operation of said tensioning and pressing means, and means, associated with said table, for guiding said marginal portion of the facing to the tensioning means.

6. A machine for conforming the marginal portion of a sole facing piece to the edge of a sole member comprising, in combination, power-operated gripper means for tensioning said marginal portion of the facing around the edge of the sole member successively in different locations along the edge of the sole member, means for pressing the marginal portion of the tensioned facing against the sole member in each location, and a yieldably mounted table for supporting the sole member and its facing piece during the operation of said gripper and pressing means.

7. A machine for conforming the marginal portion of a sole facing piece to the edge of a

sole member comprising, in combination, power-operated gripper means for tensioning said marginal portion of the facing around the edge of the sole member successively in different locations along the edge of the sole member, means for pressing the marginal portion of the tensioned facing against the sole member in each location, a yieldably mounted table for supporting the sole member and its facing, during the operation of said gripper and pressing means, and means, associated with said table, for guiding said marginal portion of the facing to the gripper.

8. A machine for conforming the marginal portion of a sole facing piece to the edge of a sole member comprising, in combination, a rest member, fixed during the operation of the machine, for engaging the sole member, power-operated gripper means for tensioning said marginal portion of the facing around the edge of the sole member adjacent to said rest member, successively, in different locations along the edge of the sole member, means for pressing the marginal portion of the tensioned facing against the sole member in each location, and a table for holding the sole member up against the rest member during the operation of said tensioning and pressing means.

9. A machine for conforming the marginal portion of a sole facing piece to the edge of a sole member comprising, in combination, a rest member for engaging the sole member, power-operated gripper means for tensioning said marginal portion of the facing around the edge of the sole member adjacent to said rest member, successively, in different locations along the edge of the sole member, means for pressing the marginal portion of the tensioned facing against the sole member in each location, a table for holding the sole member up against the rest member, during the operation of said gripper and pressing means, and means, associated with said table, for guiding said marginal portion of the facing to the gripper.

10. A machine for conforming the marginal portion of a sole facing piece to the edge of a sole member comprising, in combination, a rest member for engaging the sole member, power-operated gripper means for tensioning said marginal portion of the facing around the edge of the sole member adjacent to said rest member, successively, in different locations along the edge of the sole member, means for pressing the marginal portion of the tensioned facing against the sole member in each location, a yieldably mounted table for holding the sole member up against the rest member, during the operation of said gripper and pressing means, and means, associated with said table, for guiding said marginal portion of the facing to the gripper.
